UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed December 26, 1919, Serial No. 347,571. Renewed June 18, 1928.

My invention relates to mining apparatus. It has for its object to provide an improved mining apparatus, and more especially an improved mining machine slideable on the mine bottom and especially adapted to low vein work on the room and pillar system. A further object of my invention is to provide an improved machine, adapted to different types of cutting when desired, and more especially readily convertible at will to adapt it to either longwall or room-and-pillar cutting, i. e. to cutting with the bar laterally disposed relative to its frame as the latter moves along a face or with the bar longitudinally disposed relative to its frame as the latter moves along a face. A still further object of my invention is to provide improved means whereby a mining machine may be made capable of use when desired as either a longwall or room-and-pillar machine.

In the accompanying drawings, I have shown for purposes of illustration one embodiment which my invention may assume in practice.

In these drawings,—

Fig. 1 is a simplified plan view of a mining machine equipped with my improvement.

Fig. 2 is a detail front elevation showing my improved feed member guiding means.

Fig. 3 is a sectional view of the same taken on line 3—3 of Fig. 1.

Fig. 4 is a side elevation of the same, parts being broken away to facilitate illustration.

Fig. 5 is a diagrammatic view showing the apparatus in use as a room-and-pillar machine, the machine frame being shown in a plurality of positions.

Fig. 6 is a diagrammatic view of the apparatus in use as a longwall machine.

Fig. 7 is a side elevation of the front end of the receding side of the machine shown in full lines in Fig. 5.

Fig. 8 is a side elevation of the front end of the advancing side of the same.

In this illustrative construction I have shown a mining machine of a well known longwall type, described and claimed in my copending application Ser. No. 130,579, filed Nov. 10, 1916, the same herein (Fig. 1) including a low frame 1 slideable on its bottom on a mine bottom and carrying at one end a usual motor driven feed operating member 2 adapted to cooperate with a flexible feeding member 3, and at its opposite end a cutter bar 4 disposed substantially on the mine

bottom and pivoted at 5 on the frame 1 and a front head 6 and having a cutter chain 7 movable therearound and driven from the intermediate motor M in a well known manner; this machine being provided with improved means hereinafter described whereby the same is adapted to room-and-pillar cutting when desired.

In my improved construction, a feed guide support member 8 is fixed to the front end of the frame 1 near the rear end of the cutter bar 4 (Fig. 1), the same herein being carried upon the head 6 and provided with flanges 9 and 10 adapted to fit over the edge of the head and be clamped thereto by any suitable means, as for instance by a vertical bolt 11 extending through the head and a suitable bushing 12 and threaded into the member 10, a suitable washer, as 13, herein preferably also being disposed between the head of the bolt and the bushing to retain the latter in place. This member 8 is in turn also preferably provided with a pair of laterally extending spaced arms 14 which are disposed vertically on its side, and have pivots mounted between the upper ends of the same, as on a pivot pin 15, a swinging guide carrying member 16. This member 16 is in turn preferably also provided on its free end with a longitudinally disposed stud 17 of reduced cross section and located near the bottom in such a location as to form a suitable bearing for a rotatable guide member 18. This member 18 may be of any suitable form adapted to cooperate with any suitable type of flexible feed member, and is herein for illustrative purposes shown in the form of a chain sprocket adapted to cooperate with a flexible feed chain. As shown, a suitable bushing 19, herein of transversely divided, two-part, removable construction, is also disposed between the member 18 and the stud, both the members 18 and 19 being held in position between the washer 20 and the larger lower end of the member 17 by suitable means, such as a bolt 21.

In order that the pivoted member 16 may be suitably retained in its operative position, I have found it necessary to provide means for rigidly connecting the same to the member 8. These means may obviously assume various forms, although they are preferably of a type which may be readily connected or disconnected at will, as in room-and-pillar min-

110

ing it is desirable for the member 16 at different times to be swung into an upright position above its pivot or to be held definitely in the fixed relation with respect to the member 8 and the machine shown in Fig. 3. Herein, these means include a pin 22 movable longitudinally through suitable cooperating apertures in the arms 14 of the member 8 and in the lower portion of the member 16, the pin 10 preferably passing through the parts at a point well below the pivot 15 and above the stud 17. More specifically, it will be observed that herein this pin has one reduced end 23 receivable in a correspondingly shaped aperture 24 in the right hand member 14 (Fig. 4), a section of larger diameter 25 receivable in a correspondingly shaped slightly longer recess or bore 26 in the member 16, and a groove 27 in its body portion and longitudinally spaced from the portion 25. As shown, the pin also has fixed to its opposite end, as by a transverse pin 28, an enlarged handle or knob 29, in turn receivable in a correspondingly shaped aperture 30 in the left hand member 14, which aperture in turn communicates through a reduced neck 31, with an enlarged mouth 32 formed in the outer edge of the arm 14 in question. In a preferred form, suitable interlocking means are also provided 20 between the pin and one of the members 14, 16, as for instance by providing a ball 33 carried by the latter member and normally projected by a spring 34 into the groove 27. Thus, it will be observed that it is made possible 30 for an operator to release the parts with facility by simply pulling the pin to the left of the position shown in Fig. 4 until the portion 23 thereof clears the aperture 24 and the body portion of the pin at the left of the groove 27 is brought into the aperture 30; and then simply swinging the member 16 about its pivot, the pin then moving freely through the openings 31, 32. It will also be observed that, conversely, i. e. when the member 16 is moved 40 back toward operative position with the pin 22 in the same position, the member 16 will drop into the position shown in Fig. 3, so that, by simply pushing in the pin, the operator may lock the parts 14 and 16 together, the spring pressed ball 33 thereupon also automatically engaging the groove 27 to prevent accidental longitudinal movement of the pin.

It has also been found desirable to provide 50 means for preventing conflict between the flexible feed member 3 and the cutter chain 7, as the path of the latter is closely adjacent the member 3, when that member is passed around the member 18. These means may likewise assume various forms, being carried upon either the machine or the member 8. As the former disposition, however, ordinarily requires another separate removable attachment which would have to be removed 60 during certain operations of the machine, I 65 preferably provide these means upon the

member 8, the same herein taking the form of a downwardly extending guard or flange 35 formed on the lower flange 10 and so shaped on its opposite sides as to provide a substantial seat for the threaded end of the bolt 11 and a maximum clearance for both the cutter chain 7 and the feed chain 3 without objectionably interfering with the cuttings. Attention is further directed to the fact that in order that the rotatable guiding member 18 may be readily lubricated, I have herein provided a lubricant pocket 36 adapted to be closed by a suitable plug 37 in the lower part of the member 16 and at one side of the pin 22, the pocket 36 being extended diagonally downward and provided with a communicating bore 38 of reduced cross section leading down into the stud 17 and having a lateral port 39 extending to the periphery of the stud. 70 75 80 85

Referring again to the mining machine proper, it will be observed that the bar 4 hereinabove described as pivoted at 5 to the frame 1, is adapted to be held rigidly in a plurality of different angular relations to the frame in a well known manner, both the bar and the head 6 being provided with perforations 40 adapted to register when the bar is in different angular positions and to receive a locking pin 41, three of these perforations herein being shown in the head disposed in front and on the opposite sides of the pivot 5 and one in the bar, as in a well known arrangement. Herein, it will be noted that the sleeve 12 is shown to be conveniently disposed in one of the perforations 40 in the head 6, although obviously separate provision may be made to receive this sleeve. As a result of this angularly adjustable bar construction, it will be evident that the bar 4 and frame 1 may be 90 locked in the longitudinally disposed relation shown in Fig. 1 in such a manner as to form in effect a rigid room-and-pillar machine, or the bar may, if desired, be locked in the oppositely disposed angular relations usual in longwall mining, herein shown in Fig. 6, to 95 form a longwall machine, my improvement making it possible for the machine to be fed by its flexible feeding member when the parts are in either relation mentioned, and therefore adapting the machine to either longwall or room-and-pillar cutting. Attention 100 is also directed to the fact that I have herein provided a plurality of supplemental apertures 42 in the head 6, two being shown herein, which supplemental apertures are also adapted to receive the pin 41 when the apertures 42 in the head and the aperture 40 in the bar are brought into registry, this last mentioned feature having decided advantages in room-and-pillar cutting under bad roof conditions, as hereinafter described. 105 110 115 120 125 130

In the use of my improved construction, during continuous right or left hand longwall cutting in which the bar is disposed at

the right or left, respectively, of the frame, my improved guiding means may be carried in the unused side holes 40 on the opposite side of the head, the same then in no way conflicting with the angular movement of the parts. When, however, it is desired to utilize the machine as a room-and-pillar machine, the bar 4 is then locked by the pin 41 in the longitudinal position shown in Fig. 1, and my improved guiding device is inserted in the side opening 40 on the side adjacent the rib toward which the cut is to be made. During sumping, the flexible feed member 3 may accordingly be passed down between the frame and the rotatable guiding member 18 and connected to the face, the machine then being sumped in a well known manner, as the feed operating member 2 is rotated, the member 18 during this operation acting as an effective guide disposed close to the bottom. During transverse cutting, the flexible feed member 3 may also have one end passed laterally around the member 18 to a jack adjacent the rib mentioned, while the other end of the flexible feed member may be passed in an opposite direction from the feed operating member to the opposite rib, to which it is connected by any suitable usual means, such as a jack or take-up, the machine then operating as a usual room-and-pillar machine. By inserting my improved guiding device in the left hand opening 40 (Fig. 5) and inserting the bar pin 41 in the right hand opening 42, as shown in that figure, it will also be noted that it is possible to reduce the length of the converted machine when necessary, and thereby reduce the area which must be left clear of props. More particularly, by this arrangement it will be observed that it is possible to angle the frame 1 relative to the bar and yet operate the machine as a room-and-pillar machine, the angular position of the frame relative to the bar then bringing in the rear end of the frame so much more closely to the face as to permit of the props being placed a substantial distance closer to the machine, a feature of decided importance when operating under bad roof conditions. Obviously, through the provision of the plurality of openings 42 this feature may be used in cutting on either side, as desired.

As a result of my improved construction, it will be observed that it is made possible to utilize a single machine for either long-wall or room-and-pillar cutting, or vice versa. More particularly, it will be noted that the same enables advantage to be taken of the lower construction usually embodied in a longwall machine, in such a manner as to enable low vein work to be cut on the room and pillar system. It will also be observed that with my improved construction it is made possible to cut on this latter system in low vein work and under bad roof conditions requiring propping closely adjacent the face,

the angling of the machine frame in my improved construction enabling a longwall machine to cut on the room-and-pillar principle in as small a space as a materially shorter machine. At the same time, attention is directed to the fact that my improved converting means is of a simple and rugged type which may be readily constructed and applied to standard machines at small expense and without material change therein. The same is also of such a construction that it in no way interferes with right or left hand use of the cutting apparatus in cutting of either type, the guiding device in view of its reversible mounting being adapted to be disposed readily in a non-conflicting position, and even requiring no change in certain cutting, as for instance where the conditions require room-and-pillar cutting from right to left, and consecutive right and longwall cutting (Figs. 5 and 6), or vice versa.

While I have in this application specifically described one embodiment which my invention may assume in practice, it will be understood that this form of the same is shown for illustrative purposes and that the invention may be modified and embodied in various other forms without departing from its spirit or the scope of the appended claims.

What I claim as new and desire to secure by Letters Patent is:

1. The combination with a mining machine slideable on a mine bottom and having a motor thereon and a longitudinally extending cutter chain carrying cutter bar thereon disposed substantially on the mine bottom and having its rear end in front of said motor with the orbit of the chain wholly in front of the motor, of means for feeding said machine laterally including flexible feeding portions acting laterally on the opposite ends of said machine and having its advance portion acting in a plane between the mine bottom and the top of said bar.

2. The combination with a mining machine slideable on a mine bottom and having a motor thereon and a longitudinally extending cutter chain carrying cutter bar thereon disposed substantially on the mine bottom and having its rear end in front of said motor with the orbit of the chain wholly in front of the motor, of means for feeding said machine laterally including flexible feeding portions acting laterally on the opposite ends of said machine and having its advance portion acting substantially in the plane of said cutter bar.

3. The combination with a mining machine slideable on a mine bottom and having a motor thereon and a longitudinally extending cutter bar thereon disposed substantially on the mine bottom and having its rear end in front of said motor with the orbit of the chain wholly in front of the motor, of flexible feeding means acting laterally on the opposite

ends of said machine including a feed guide disposed adjacent the front end of said machine, and means carried by said frame forming an abutment between said cutter bar and said guide while permitting a free egress of cuttings from said bar.

4. The combination with a mining machine 10 slideable on a mine bottom including a motor thereon and a longitudinally extending cutter chain carrying cutter bar thereon disposed substantially on the mine bottom and having its rear end in front of said motor with the orbit of the chain wholly in front of the motor, of flexible feeding means acting laterally on the opposite ends of said machine, and means presenting an abutment between an element of said feeding means and said bar and a cuttings outlet on the opposite side of said bar from said abutment.

20 5. The combination with a mining machine slideable on a mine bottom and having a motor thereon and a longitudinally extending cutter chain carrying cutter bar thereon disposed substantially on the mine bottom and having 25 its rear end in front of said motor with the orbit of the chain wholly in front of the motor, of means for feeding said machine laterally in opposite directions acting on the opposite ends thereof including guide means 30 operative in either direction of feed and disposed on said machine adjacent one end thereof and substantially in a plane between the mine bottom and the top of said bar.

35 6. The combination with a mining machine slideable on a mine bottom and having a motor thereon and a longitudinally extending cutter chain carrying cutter bar thereon disposed substantially on the mine bottom and having 40 its rear end in front of said motor with the orbit of the chain wholly in front of the motor, of means for feeding said machine laterally in opposite directions acting on the opposite ends thereof including guide means operative 45 in either direction of feed and disposed on said machine adjacent one end thereof and substantially in the plane of said bar, and spacing means between said guide member and bar likewise operative in either direction of feed.

50 7. The combination of a mining machine slideable on a mine bottom including a motor thereon and a cutter chain carrying cutter bar thereon terminating in advance of said motor with the orbit of the chain wholly in 55 front of the motor, of means for disposing said bar in fixed positions longitudinally and transversely of said machine, and flexible feeding means including a feed portion acting longitudinally of said machine when said bar is transversely disposed and a plurality 60 of feeding portions acting on the opposite ends of said machine with its advance portion acting in a plane between the mine bottom and the top of said bar when the latter is longitudinally disposed.

8. In a mining apparatus, a longwall machine comprising laterally disposed cutting means and flexible traction feeding means, and means whereby said machine may be converted into a room-and-pillar machine with 70 said cutting mechanism longitudinally disposed and said flexible traction feeding means in the plane of said cutting means.

9. In a mining apparatus, a room-and-pillar machine having longitudinally disposed cutting means thereon and feeding means comprising a flexible traction member disposable substantially in the same plane as said cutting means, and means whereby said machine may be converted into a longwall machine with its cutting means laterally disposed.

10. In a mining apparatus, a frame slideable on its bottom on the mine bottom, cutter mechanism comprising a cutter bar projecting therefrom at one end thereof, flexible feeding means having advance and receding flexible feeding portions extending in opposite directions from the opposite ends of the frame, rotatable feed operating means on said frame adjacent the other end thereof and cooperating with said feeding means whereby said feeding portions may be drawn in by power, and means whereby said cutter bar may be disposed laterally or longitudinally and said flexible feeding means may be reeved for longwall and for room-and-pillar cutting respectively.

11. In a mining apparatus, a frame slideable on its bottom on the mine bottom, cutting mechanism comprising a cutter bar projecting from said frame at one end thereof, a motor on said frame driving said cutting mechanism, flexible feeding means having advance and receding flexible feeding portions extending in opposite directions from the opposite ends of the frame, rotatable feed operating means on said frame adjacent the end of said motor remote from said cutter bar and cooperating with said flexible feeding means whereby said feeding portions may be drawn in by power, and means whereby said cutter bar may be disposed laterally or longitudinally and said flexible feeding means may be reeved for longwall or room-and-pillar cutting respectively.

12. In a mining apparatus, a room-and-pillar machine slideable on the mine bottom during cutting and including an elongated frame and a relatively movable cutter bar, 120 means for reversibly relatively angularly disposing said elements, and means including oppositely extending flexible portions acting laterally on the opposite ends of said elongated frame for feeding and guiding the machine laterally along a face when the elements thereof are so disposed.

13. In a mining apparatus, a mining machine having a pivoted cutter bar, means for fixing the latter in different angular relations 120

for longwall and room-and-pillar cutting, and means for feeding said machine in opposite directions during operation as a room and pillar machine including a feed member guide 5 member disposable at will in positions on opposite sides of the bar pivot for converting said machine into a room and pillar machine.

14. In a mining apparatus, a machine having a pivoted cutter bar, means for positioning the same angularly relative to said machine including a plurality of apertures in the latter, and a feed member guiding member disposable in certain of said apertures.

15. In a mining apparatus, a longwall machine having a pivoted cutter bar, and means for positioning the latter for right or left hand cutting including a plurality of apertures in said machine, and a feed member guiding member disposable in different ones 20 of said apertures.

16. In a mining apparatus, a machine having a pivoted cutter bar, means for positioning the latter in different positions including a plurality of apertures adjacent the bar 25 pivot, and a feed member guiding member disposable in one of said apertures.

17. In a mining machine, a machine frame, a pivoted cutter bar thereon, means for positioning said bar in different angular relations 30 including a series of apertures adjacent the bar pivot, and a feed member guiding member disposable in any of a plurality of said apertures.

18. In a mining apparatus, a mining machine having a pivoted cutter bar, means for positioning the latter in a plurality of angular relations with said machine including a longitudinally disposed relation, a feed member guiding member carried on said machine 40 adjacent the bar pivot and also adjustable to a plurality of positions, and flexible lateral feeding means including power operated and controlled flexible portions acting transversely of the opposite ends of said machine and one engaging said guiding member when said bar is longitudinally disposed.

19. In a mining apparatus, a mining machine having a pivoted cutter bar, means for positioning the latter in a plurality of angular positions, a feed member guiding member, and means for disposing the same adjacent the bar and in positions on opposite sides of the bar pivot but in the plane of said bar.

20. In a mining machine, a machine frame, a pivoted cutter bar thereon, means for positioning said bar in different angular positions including a series of apertures located circumferentially around the bar pivot, and a feed member guiding member disposable in one of said apertures.

21. In a mining machine, a frame, a cutter bar pivoted thereon, means for positioning the latter in a plurality of angular relations, a feed member guiding member carried on said frame adjacent the pivot of said bar and

substantially in the same plane with said bar, and a guard between said member and bar.

22. In a mining machine, a frame, a cutter bar pivoted thereon, means for positioning the latter in a plurality of angular relations, 70 a feed member guiding member carried on said frame adjacent the pivot of said bar, and a guard carried by said member and disposed between the latter and said bar.

23. In a mining machine, a frame, a pivoted bar thereon, means for positioning the latter in different angular relations including a plurality of apertures in said frame, a cooperating removable feed member guiding member supported in an unused aperture, and removable 80 guard means disposed between said member and said bar.

24. In a mining apparatus, a feed member guiding member comprising a supporting member adapted to be attached to a machine 85 frame, a pivoted guide carrying member on said supporting member, a guide member rotatably mounted on the latter, and means for releasably connecting said support and swinging member.

25. In a mining apparatus, a feed member guiding member comprising a supporting member adapted to be attached to a machine frame, a pivoted guide carrying member on said supporting member, a guide member rotatably mounted on the latter, a pin extending 95 through said support and swinging member, and means on said pin and support for releasing said pivoted member upon a partial withdrawal of said pin.

26. In a mining apparatus, a feed member guiding member comprising a supporting member adapted to be attached to a machine frame, a pivoted guide carrying member, a guide member rotatably mounted on the latter, a pin extending through said support and swinging member, means on said pin and support for releasing said pivoted member upon a partial withdrawal of said pin, and means 105 acting between said pin and one of said members for inhibiting accidental longitudinal pin movement.

27. In a mining machine, a feed member guide supporting member having a flange provided with a depending guard thereon, a swinging guide carrying member pivoted on said supporting member, a rotary guide member journaled on said swinging member and disposable in one position spaced apart from but adjacent said depending guard, and releasable means for securing the elements in said position.

28. In a mining machine, a feed member guide supporting member having spaced flanges, one provided with a depending guard 115 thereon, means for clamping said flanges to a support, a swinging guide carrying member pivoted on said supporting member, a rotary guide member journaled on said swinging member and disposable in one position spaced 120 from the support.

apart from but adjacent said depending guard, and releasable means for securing the elements in said position.

29. In a mining apparatus, a feed member 5 guiding member comprising a supporting member adapted to be attached to a machine frame, a pivoted guide carrying member depending from its pivot when in operative position and movable upward into an inoperative position, a guide member mounted on the latter and rotatable about an axis substantially perpendicular to said pivot, and means for releasably connecting said support and pivot member.
- 15 30. In a mining apparatus, a feed member guiding member comprising a supporting member adapted to be attached to a machine frame, a pivoted guide carrying member depending from its pivot and movable upward 20 into inoperative position, a guide member mounted on the latter and rotatable about an axis substantially perpendicular to said pivot, and means acting adjacent the free end of said guide carrying member for releasably 25 connecting said support and member.

31. In a mining apparatus, a feed member guiding member comprising a supporting member adapted to be attached to a machine frame, a pivoted guide carrying member, a 30 guide member mounted on the latter and rotatable about an axis substantially perpendicular to said pivot, and a cooperating guard carried on said supporting member and disposed adjacent said guide member.

32. The combination with a mining machine slidable on a mine bottom and having a 35 motor thereon and a cutter chain carrying cutter bar disposed substantially on the mine bottom and so disposed that its projection and that of said motor on the mine bottom do not overlap and pivotable about an axis between its ends, and means for holding the same in 40 positions at an angle to or in alignment with the major dimension of said mining machine, of means for feeding said machine to effect cutting with said bar in either of said positions including when said bar is in the last 45 mentioned position flexible feeding portions acting laterally on the opposite ends of the machine body of which said advance portion acts in a plane between the mine bottom and the top of the bar.

33. The combination with a mining machine slidable on a mine bottom and having 55 a motor thereon and a cutter chain carrying cutter bar disposed substantially on the mine bottom and so disposed that its projection and that of said motor on the mine bottom do not overlap and pivotable about an axis between its ends, and means for holding the same in 60 positions at an angle to or in alignment with the major dimension of said mining machine, of means for feeding said machine to effect cutting with said bar in either

of said positions including when said bar is 65 in the last mentioned position flexible feeding portions acting laterally on the opposite ends of the machine body of which said advance portion acts substantially in the plane 70 of the cutter bar.

34. In a mining apparatus, a frame, cutting mechanism comprising a cutter bar projecting from one end thereof, a flexible feeding means, rotatable feed operating means on said frame and cooperating with said feeding means, and means whereby said cutter bar may be disposed laterally or longitudinally and said flexible feeding means may be reeved for longwall and room and pillar cutting respectively with the portion of said flexible 80 feeding means in advance of said machine lying substantially in the plane of said bar.

35. In a mining apparatus, a room and pillar machine operative to cut in either direction across a face including an elongated 85 frame and a relatively movable cutter bar, means whereby the effective length of said elements may be shortened during cutting irrespective of whether the cut be from left to right or vice versa, and means including oppositely extending flexible portions acting laterally on the opposite ends of said elongated machine for feeding and guiding the machine laterally along the face when the elements thereof are so disposed.

36. In a mining apparatus, a room and pillar mining machine adapted to cut in either direction across a face and including an elongated frame and a relatively movable cutter bar, means for relatively angularly disposing said elements and fixing them in such relation that said machine frame may make the same angle with the portion of the face in advance thereof in either direction of travel, and means including oppositely extending flexible 100 portions acting laterally on the opposite ends of said elongated frame for feeding and guiding the machine laterally along the face when the elements thereof are so disposed.

37. In a mining apparatus, a feed member guiding member comprising a supporting member adapted to be attached to a machine frame in a plurality of different positions, a pivoted guide carrying member, a guide member mounted on the latter and rotatable about an axis substantially perpendicular to said pivot, and means for releasably connecting said support and pivoted member.

38. In a mining apparatus, a feed member guiding member comprising a supporting member adapted to be attached to a machine frame at either side thereof, a pivoted guide carrying member, a guide member mounted on the latter and rotatable about an axis substantially perpendicular to said pivot, and means for releasably connecting said support and pivoted member.

39. In a mining apparatus, a feed member

guiding member comprising a supporting member adapted to be attached to a machine frame, a guide carrying member pivoted on said supporting member for movement relative to the latter resulting in a change in the angular relation of said guide carrying member to the major dimension of said supporting member, a guide member mounted on the pivoted guide carrying member and rotatable about an axis substantially perpendicular to said pivot, and means for releasably connecting said support and pivoted member.

40. In a mining apparatus, a feed member guiding member comprising a supporting member adapted to be attached to a machine frame, a pivoted guide carrying member, a guide member mounted on the latter and rotatable about an axis substantially perpendicular to said pivot, and means for releasably connecting said support and pivoted member with the axis of said rotatable guide member disposed in a vertical plane passing through said pivot and below said pivot in said plane.

41. In a mining machine of the type adapted to cut in opposite directions, a machine frame slidable directly on its bottom on the mine bottom during operation of the machine, a horizontal motor carried thereby, reversible cutting mechanism driven by said motor including a horizontal plane cutter chain carrying cutter bar projecting lengthwise of said frame during lateral cutting and disposed substantially on the mine bottom, said motor and cutter bar being so disposed that the projections of said bar and motor do not overlap, the top and bottom plane surfaces of said bar lying in planes intersecting said motor, and means driven by said motor for effecting feeding of the machine laterally to effect cutting in either direction including flexible feeding means having power operated and controlled advance and receding

flexible feeding portions acting laterally on the opposite ends of said machine frame.

42. In a mining machine of the type adapted to cut in opposite directions, a frame slidable directly on its bottom on the mine bottom during operation of the machine, a horizontal motor carried thereby, the vertical dimension of said motor substantially determining the height of the machine, reversible cutting mechanism driven by said motor including a horizontal plane cutter chain carrying cutter bar projecting lengthwise of said frame during lateral cutting and disposed substantially on the mine bottom, the top and bottom plane surfaces of said bar lying in planes intersecting said motor, and mechanism driven by said motor to effect feeding of the machine laterally to effect cutting in either direction including power operated and controlled flexible feeding portions acting laterally on the opposite ends of said machine frame and having their free ends anchored at points extraneous of the machine.

43. In a mining machine, an elongated machine frame slidable directly on its bottom on the mine bottom, cutting mechanism including a cutter bar pivoted on said frame for swinging movement into positions wherein said bar is disposed at either side of the frame for longwall cutting, or lengthwise thereof for room and pillar cutting, means for feeding the machine laterally to effect cutting with said bar in any of its positions including when said bar is disposed lengthwise of the machine, and means whereby the effective length of the machine may be varied during lateral cutting, said feeding means including flexible feeding portions acting laterally on opposite ends of said frame in any length thereof.

In testimony whereof I affix my signature.
MORRIS P. HOLMES.

CERTIFICATE OF CORRECTION.

Patent No. 1,704,665.

Granted March 5, 1929, to

MORRIS P. HOLMES.

It is hereby certified that error appears in the printed specification of the above numbered patent requiring correction as follows: Page 1, line 59, before the word "motor" insert the word "horizontal"; page 3, line 85, for the word "and" read "hand"; and that the said Letters Patent should be read with these corrections therein that the same may conform to the record of the case in the Patent Office.

Signed and sealed this 9th day of April, A. D. 1929.

(Seal)

M. J. Moore,
Acting Commissioner of Patents.

DISCLAIMER

1,704,665.—*Morris P. Holmes, Claremont, N. H. MINING APPARATUS. Patent dated March 5, 1929. Disclaimer filed January 9, 1943, by the assignee, Sullivan Machinery Company.*

Hereby enters this disclaimer to claim 13 in said specification.
